MOUNT

Samuel G. Green, Gray, Ga.

Application January 25, 1935, Serial No. 3,441

2 Claims. (Cl. 248—186)

(Granted under the act of March 3, 1883, as
amended April 30, 1928; 370 O. G. 757)

The invention described herein may be manufactured and used by or for the Government for governmental purposes, without the payment to me of any royalty thereon.

5 This invention relates to a mount and is particularly applicable as a mount for light guns of the class generally described as machine guns.

In combat it frequently becomes necessary to make immediate and rapid changes from one 10 target to another and between different types of targets. In following a rapidly moving aerial target the gun should be mounted for free traversing movement but on slow moving ground targets better results are obtained by employing a 15 controlled traversing movement through a gear system.

The purpose of this invention is to provide a light mount in which a standard or similar supporting member is arranged to be readily clutched and declutched with a gear system.

20 To these and other ends, the invention consists in the construction, arrangement and combination of elements described hereinafter and pointed out in the claims forming a part of this 25 specification.

A practical embodiment of the invention is illustrated in the accompanying drawing, wherein:

Fig. 1 is a plan view of the improved mount.
30 Fig. 2 is a longitudinal sectional view showing the standard clutched to the gear system.

Fig. 3 is a similar fragmentary view showing the standard declutched from the gear system.

Referring to the drawing by characters of 35 reference, there is shown a gear wheel 5 having an elongated hollow hub 6 whereby it is mounted vertically on a pair of anti-friction bearing units 7—7 in a housing 8. The gear wheel is driven by a pinion 9 on a shaft 10 which is mounted 40 in the housing 8 and has a handwheel 11 on one end. The upper part of the gear wheel is formed into a socket by an annular wall 12 which terminates in a flange 13 that rests on the upper edge of the housing.

45 A standard 14, adapted for example, to carry a gun, is formed with a base 15 receivable within the annular wall 12 and with a flange 16 adapted to rest on the flange 13 of the gear wheel. A pintle 17 depending from the base 15 passes 50 through the hollow hub 6 and has its lower extremity projecting below the hub. The lower extremity is formed with an annular groove 18 for receiving a latch which, in the present instance, is in the form of a ring 19 with an 55 internal diameter that is greater than the diam-

eter of the pintle. The ring is moved into the groove 18 by a spring 20 and it is moved out of the groove by a bolt 21. The latch is carried in a casing 22 which includes a cover 23 and is fitted in the lower end of the housing.

5 The upper face of the gear wheel 5, which forms the floor of the socket constituted by the annular wall 12, is provided with a series of annularly arranged recesses 24. The recesses are adapted to receive a plunger 25 which is 10 mounted in the base 15 of the standard and, under the influence of a spring 26, is projected through the base to form a coupling between the standard and the gear wheel. The spring 26 embraces the plunger and is confined between 15 a collar 27 on the plunger and a nut 28 threaded in the bore of a boss 29 on the upper face of the base.

The wall of the boss is provided with a recess or notch 30 preferably having one vertical edge 20 31 and one inclined edge 32, the latter constituting a cam. The upper edge of the boss is provided with a recess 33 positioned adjacent the inclined edge of the notch. A bar 34 secured to the plunger and disposed perpendicularly 25 thereto is arranged to engage the recess 33 as shown in Fig. 3 or enter the notch as shown in Fig. 2, these positions corresponding respectively to the unlocked and locked position of the plunger. By virtue of this arrangement the standard 30 may be readily clutched to and declutched from the gear wheel.

The handwheel 11 is provided with a scale 35 which is readable against an index 36 on the housing 8. A second scale 37 is provided on a 35 ring 38 which is rotatably mounted on the housing adjacent the base 15 of the standard and is held in position of adjustment by a clamp 39. The scale 37 is readable against an index 40 on the base.

40 When the standard 14 is clutched to the gear wheel 5 through the plunger 25 it can only be rotated about its axis through the pinion 9 on the shaft 10. When the plunger is disengaged from the gear wheel by movement to the position shown in Fig. 3, the standard and the gear wheel 45 can be rotated independently of each other.

I claim:

1. In a gun mount, a housing, a gear wheel mounted in the housing and having a socket in its upper part, the face of the gear wheel that forms the floor of the socket having a plurality of recesses, a standard having a base receivable in the socket of the gear wheel, a plunger mounted in the base of the standard, a spring normally 50 55

urging the plunger into any one of the recesses, a bar on the upper end of the plunger, and a member on the standard having a cam surface and a recess adjacent the upper end of the cam surface, the cam surface and recess being engageable by the bar of the plunger.

5. 2. In a gun mount, a housing, a gear wheel mounted in the housing and having a socket in its upper part, the face of the gear wheel

that forms the floor of the socket having a plurality of recesses, a standard having a base receivable in the socket of the gear wheel, a plunger mounted in the base of the standard, a spring normally urging the plunger into any one of the 5 recesses, and means for holding the plunger clear of the gear wheel.

SAMUEL G. GREEN.
